UNITED STATES PATENT OFFICE

CHARLES FEY, OF DETROIT, MICHIGAN, ASSIGNOR TO CHICAGO PNEUMATIC TOOL COMPANY, OF NEW YORK, N. Y., A CORPORATION OF NEW JERSEY

CUSHION SHOE FOR RAMMER AND TAMPER BUTTS

Application filed October 4, 1928. Serial No. 310,268.

This invention relates to ramming and tamping and more specifically to certain apparatus, such as butts, used in such operations.

5 A particular object of the invention is to avoid damage to moulds and forms from the use of power apparatus. Another object is to cushion the blow delivered by power operated tamping and ramming devices without impairing the effectiveness of the same. Another object is to provide a simple and inexpensive cushion attachment or shoe applicable to standard butts. Still further objects will be apparent from the detailed description which follows.

In order to illustrate the invention, one concrete embodiment thereof is shown in the accompanying drawings, in which:

Fig. 1 is a side elevational view showing the 20 shoe in place and ready for use;

Fig. 2 is a top plan view of the cushion shoe; and

Fig. 3 is a sectional view substantially on the line 3—3 of Fig. 2.

25 The cushion member of the present application is adapted and intended for use with standard butts used in tamping and ramming operations. In Fig. 1, the shoe 4 is shown applied to a butt A secured upon the end of a shaft B which projects from the cylinder C of a tool, such as a pneumatic rammer or other machine, adapted to impart reciprocatory motion to shaft B. The particular form of butt herein disclosed is generally frustoconical in 35 shape and provided with a circular, flat working face α which is intended for direct contact with the work. The butt is ordinarily of metal, the weight of which may be lightened by leaving the interior hollow; additional 40 lightness may be secured by making it of aluminum or from aluminum alloy.

To protect the moulds and forms from injury, the cushion shoe 4 is arranged to enclose the lower portion of the butt A. Shoe

45 4 may be of any suitable material and is arranged to provide a thick cushion portion or face 5 for the working face α of the butt. Projecting substantially transversely from the peripheral part of the upper face of portion 50 5 is a wall 6 annular in shape and tapering in-

wardly whereby shoe 4 appears as a hollow member with a socket or recess 7 conforming substantially to and arranged to fit the exterior of butt A. By preference the wall 6 is of suitable elastic material so that it may be distorted to enlarge the restricted opening to recess 7 to permit the insertion therethrough of the large end of butt A, the wall 6 then yieldingly gripping the wall of the frustoconical portion of the butt and retaining the shoe on the butt by the resiliency of wall 6. In the present instance the lower portion of recess 7 is substantially cylindrical, as indicated at 7^a, and tapers inwardly thereabove in parallelism with the exterior face of wall 6, as indicated at 7^b (Figs. 1 and 3). By preference the shoe 4 is moulded or formed in one piece of elastic material, such as rubber or a composition containing rubber or having the general characteristics of rubber.

70 I claim as my invention:

1. In tamping and ramming apparatus, in combination, a reciprocable shaft, a butt thereon of rigid material having a working face, and means applicable to said butt for cushioning the blow of the latter thereby to prevent damage to moulds and forms.

2. In tamping and ramming apparatus, in combination, a reciprocable shaft, a butt thereon of rigid material having a working face, and means for applying a resilient cushion to the working face of said butt.

3. In tamping and ramming apparatus, in combination, a reciprocable shaft, a butt thereon of rigid material having a working face, and a cushion member enclosing the entire lower portion of said butt.

4. In tamping and ramming apparatus, in combination, a reciprocable shaft, a butt thereon of rigid material having a working face, and a cushion member enclosing the entire lower portion of said butt, said member having an elastic portion for gripping the butt to hold the member in place.

5. In tamping and ramming apparatus the combination with a butt having a working face and a tapered portion thereabove, of a hollow cushion member arranged to receive and enclose the lower portion of said butt and having a restricted portion capable of being

100

distorted to pass over said face and of yielding-
ingly gripping the tapered portion of the
butt.

6. In tamping and ramming apparatus the
combination with a butt having an annular
5 working face and a frustoconical portion
thereabove, of a cushion member of elastic
material and of similar shape providing
therewithin an opening to fit the lower portion
10 of said butt, said member being distorted
when applied to said butt and retaining itself
thereon by its own resiliency.

7. A cushion shoe for a rammer or tamper
butt of substantially frustoconical form com-
15 prising a member shaped to fit over the ex-
terior of the butt and having a tapered upper
portion of elastic material providing a re-
stricted opening, said portion being distort-
able to permit the insertion of the large end
20 of the butt through said opening and retain-
ing the member on the butt by its own re-
siliency.

8. A cushion shoe for a rammer or tamper
butt of substantially frustoconical form com-
25 prising a member formed integrally of elas-
tic material providing a flat face and a hollow
frustoconical portion extending there-
from and applicable to and removable from
the butt by distortion of said hollow portion.

30 9. A rubber shoe for covering the lower
portion of a butt of substantially conical
form above its working face comprising a
hollow member moulded in one piece with a
thick circular portion to cover the working
35 face of the butt and an annular inwardly ta-
pered wall extending from one face of said
portion, said wall and portion forming a re-
cess to receive said lower portion of said butt,
which recess is substantially cylindrical adja-
40 cent said circular portion and is frustoconical
thereabove.

Signed by me at Detroit, in the county of
Wayne and State of Michigan this 29th day
of September, 1928.
